UNITED STATES PATENT OFFICE.

SIDNEY H. WOODRUFF, OF BUFFALO, NEW YORK.

REINFORCEMENT FOR CONCRETE GIRDERS, &c.

No. 820,839.

Specification of Letters Patent.

Patented May 15, 1906.

Application filed February 1, 1906. Serial No. 299,003.

To all whom it may concern:

Be it known that I, SIDNEY H. WOODRUFF, a citizen of the United States, residing at Buffalo, in the county of Erie and State of New York, have invented a new and useful Improvement in Reinforcements for Concrete Girders, Beams, &c., of which the following is a specification.

This invention relates to a metal reinforcement for concrete girders, beams, and the like, and has for the object to provide a reinforcement of this character whereby the greatest amount of strength is furnished for the amount of metal used and which can be wholly put up or assembled on the ground-floor or in the blacksmith-shop ready for use in the building where intended, thereby saving considerable time in erecting the building and reducing the cost thereof proportionally.

In the accompanying drawings, Figure 1 is a vertical longitudinal section showing a girder or beam strengthened by one form of my improved reinforcement. Figs. 2 and 3 are cross-sections thereof in lines 2-2 and 3-3, Fig. 4 is a cross-section similar to Figs. 2 and 3, showing another application of this reinforcement. Fig. 5 is a vertical longitudinal section of a concrete girder or beam provided with a modified form of my improved reinforcement. Fig. 6 is a cross-section in line 6-6, Fig. 5. Fig. 7 is a cross-section similar to Fig. 6, showing a modification thereof.

Similar letters of reference indicate corresponding parts throughout the several views.

A represents the girder, beam, roof, floor, or other horizontally-extending part of a concrete building which is supported at its ends on upright walls or posts B.

In the construction represented in Figs. 1, 2, and 3 a main tension member, bar, or rod C is arranged lengthwise and horizontally in the lower part of the girder. This rod is made of comparatively heavy round steel and is straight throughout its length and has its ends turned upwardly at an angle to the main part of the rod, so as to form lugs or hooks e, which when embedded or anchored in the concrete assist in holding the rod against lengthwise displacement in the girder.

In the upper part of the girder or beam is arranged a compression member, rod, or bar D, which extends lengthwise throughout the same and is provided at its ends with downwardly-projecting hooks or lugs d, which are embedded or anchored in the concrete and

prevent longitudinal displacement of the compression-rod.

E F represent two shearing members, rods, or bars which are adapted to prevent the girder or beam from being fractured or broken by any shearing strains to which the same are subjected. Each of these shearing-rod consists of a lower central horizontal portion g, two intermediate inclined portions h, which extend upwardly and outwardly from opposite ends of the central part, upper horizontal portions i, projecting outwardly from the upper ends of the inclined portions, and downwardly-projecting anchoring-hooks j, arranged at the outer ends of the upper horizontal portions i. The lower shearing member E has its inclined parts arranged near the ends of the beam or girder, while the upper shearing member has its inclined parts arranged a greater distance from the ends of the girder. This relative location of the inclined parts of the shearing member is produced by making the horizontal portion g of the lower shearing member of greater length than the corresponding part of the upper shearing member, as shown in Fig. 1. The shearing members are practically of the same length as the lower tension member and upper compression member, this relative proportion of the parts being obtained by making the upper horizontal parts i of the upper shearing member of greater length than the corresponding parts of the lower shearing member.

In assembling the main members of the concrete reinforcement the central part g of the lower shearing member is interposed between the corresponding parts of the tension member and the upper shearing member and the upper horizontal parts of the upper shearing member are interposed between the upper horizontal end portions i' of the lower shearing member and the compression member. The hooks at the ends of the upper shearing member fit between the hooks at the ends of the compression member and the ends of the lower shearing member, whereby these parts are reliably held against endwise or longitudinal displacement relatively to each other.

k l m m represent a plurality of vertical stirrups which are arranged in a horizontal row throughout the length of the main reinforcing members or bars. These stirrups are secured to the tension and compression members and the upper and lower horizontal

parts of the shearing members by winding the ends of the stirrups around the same. The central stirrups *k* are wrapped or wound at their upper ends only around the compression member, while their lower ends are wrapped or wound around the central parts of the tension member and the central horizontal parts of the upper and lower shearing members. The outer stirrups *l* are wrapped or wound at their lower ends only around the tension member, while their upper ends are wrapped or wound around the end portions of the compression member and upper and lower shearing members. The inner intermediate stirrups *m* are connected at their upper ends only with the compression member, while their lower ends are wound or wrapped around the tension member and the adjacent lower horizontal part of the lower shearing member, while the middle parts of these stirrups are secured to the adjacent inclined portions of the upper shearing member by wire ties *o*. The outer intermediate stirrups *n* are wound or wrapped at their lower ends only around the tension member and at their upper ends around the compression member and upper horizontal ends of the upper shearing member, while their central parts are secured by wire ties *p* to the inclined portions of the lower shearing member. This reinforcement as a whole can be erected complete on the ground or in the blacksmith-shop, where this work may be done more easily, quickly, and cheaply, permitting of embedding the same into the beam or girder for which it is intended without requiring any further attention from an iron-worker and enabling the work to be completed solely by the laborers, thereby avoiding an unnecessary number of men around the work, whereby the progress of the work is facilitated and the cost thereof reduced accordingly. My improved concrete reinforcement has its several parts so constructed that they are reliably held in place relatively to each other and operate conjointly to resist any destructive force to which the beam, girder, or other concrete body in which the same is embedded may be subjected. By turning the hooks of the tension member upwardly and those of the compression and shearing members downwardly the reinforcement not only can be handled more freely without liability of catching against objects, but the mass of concrete at the ends of the girder by this means is securely interlocked with all of the reinforcing members, thereby obtaining the maximum strength in the girder or beam with a minimum use of metal.

When the concrete beam or girder which is to be reinforced is comparatively narrow, it is only necessary to employ a singular reinforcing structure of the described character, as shown in Figs. 2 and 3; but if the beam or girder is of considerable width or designed to

carry a greater load a plurality of such reinforcing structures may be employed side by side in the same beam or girder, as illustrated in Fig. 4.

When the load to which the beam or girder is to be subjected is more moderate than that for which the reinforcement shown in Figs. 1, 2, and 3 is intended, the upper heavy longitudinal compression rod or member and the central stirrups may be omitted and comparatively small compression rods or wires *q* may be arranged lengthwise above the horizontal upper parts of the upper shearing member and extended from the outer ends thereof to a point vertically in line with the ends of the central horizontal portion of the upper shearing member, as shown in Fig. 5. When thus used, the small wires *q* serve principally as a means for holding the inner stirrups in place at their upper ends while packing the concrete around the same; but they also serve in a measure as compression members.

When only a single set of tension and shearing members is employed, it is only necessary to employ a single set of stirrup-retaining wires *q*, as shown in Fig. 6; but if two sets of tension and shearing members are employed, as would be the case when reinforcing a comparatively wide girder, then the number of retaining-wires *q* is increased correspondingly, as shown in Fig. 7.

When the reinforcement is applied to the girder or beam in a roof, the compression member may be elevated at the center and inclined toward both ends in conformity with the inclination of the roof, as shown in Fig. 1; but when the reinforcement is applied to the girder or beam of a straight floor the compression member may be made straight to conform to the floor. In Fig. 5 the reinforcement is represented in the girder of a floor, and the retaining-wires and end portions of the shearing members have therefore been shown horizontally accordingly.

I claim as my invention—

1. A reinforcement for concrete girders, beams, &c., comprising a lower horizontal tension-rod, and upper and lower shearing-rod each having a lower central horizontal part, inclined parts extending upwardly and outwardly from opposite ends of the central part and upper horizontal part extending outwardly from the ends of said inclined parts, the lower horizontal part of the lower shearing-rod being longer than that of the upper shearing-rod and interposed between the same and the central part of the tension-rod and the horizontal ends of the upper shearing-rod being longer than those of the lower shearing-rod and arranged above the same, substantially as set forth.

2. A reinforcement for concrete girders, beams, &c., comprising a lower horizontal tension-rod, upper and lower shearing-rod,

each having a lower central horizontal part, inclined parts extending upwardly and outwardly from opposite ends of the central part and upper horizontal parts extending outwardly from the end of said inclined parts, the lower horizontal part of the lower shearing-rod being longer than that of the upper shearing-rod and interposed between the same and the central part of the tension-rod 10 and the horizontal ends of the upper shearing-rod being longer than those of the lower shearing-rod and arranged above the same, means for connecting the central parts of the tension-rod, upper shearing-rod and lower shearing-rod, and means for connecting the horizontal end portions of the upper and lower shearing-rods, substantially as set forth.

3. A reinforcement for concrete girders, beams, &c., comprising a lower horizontal tension-rod, upper and lower shearing-rods each having a lower central horizontal part, inclined parts extending upwardly and outwardly from opposite ends of the central part, 25 and upper horizontal parts extending outwardly from the ends of said inclined parts, the lower horizontal part of the lower shearing-rod being longer than that of the upper shearing-rod and interposed between the same and the central part of the tension-rod 30 and the horizontal ends of the upper shearing-rod being longer than those of the lower shearing-rod and arranged above the same, and upright wire stirrups wound at their lower ends around said tension-rod and lower horizontal parts of said shearing-rods and at their upper ends around the horizontal end parts of the upper and lower shearing-rods, substantially as set forth.

4. A reinforcement for concrete girders, beams, &c., comprising a lower horizontal tension-rod, upper and lower shearing-rods each having a lower central horizontal part, inclined parts extending upwardly and outwardly from opposite ends of the central part and upper horizontal parts extending outwardly from the ends of said inclined parts, the lower horizontal part of the lower shearing-rod being longer than that of the upper shearing-rod and interposed between the same and the central part of the tension-rod 45 and the horizontal ends of the upper shearing-rod, being longer than those of the lower shearing-rod and arranged above the same, an upper compression-rod, and upright stirrups secured at their lower ends to said tension-rod and lower parts of the shearing-rods while their upper ends are secured to the ends of the shearing-rods and to said upper compression-rod, substantially as set forth.

5. A reinforcement for concrete girders, beams, &c., comprising a lower horizontal tension-rod, an upper horizontal compression-rod, upper and lower shearing-rods each having a lower central horizontal part, inclined intermediate parts which extend upwardly and outwardly from the opposite ends of the central part and horizontal end parts which extend outwardly from the upper ends of the inclined parts, the horizontal lower part of the lower shearing-rod being longer than that of the upper shearing-rod and interposed between the same and the tension-rod and the end parts of the upper shearing-rod being longer than the corresponding parts 70 of the lower shearing-rod and interposed between the same and the upper compression-rod, and upright stirrups wound at their lower ends around the tension-rod and the horizontal lower parts of the shearing-rods while 80 their upper ends are wound around the compression-rod and horizontal end parts of the shearing-rods, substantially as set forth.

6. A reinforcement for concrete girders, beams, &c., comprising a lower horizontal tension-rod, an upper horizontal compression-rod, upper and lower shearing-rods each having a lower central horizontal part, inclined intermediate parts which extend upwardly and outwardly from opposite ends of 85 the central part and horizontal end parts which extend outwardly from the upper ends of the inclined parts, the horizontal lower part of the lower shearing-rod being longer than that of the upper shearing-rod and interposed between the same and the tension-rod and the end parts of the upper shearing-rod being longer than the corresponding parts 90 of the lower shearing-rod and interposed between the same and the upper compression-rod, upright stirrups wound at their lower ends around the tension-rod and the horizontal lower parts of the shearing-rods while 95 their upper ends are wound around the compression-rod and horizontal end parts of the shearing-rods, upwardly-turned hooks arranged at the ends of the tension-rod, and downwardly-turned hooks arranged at the ends of compression-rod and the shearing-rods, the hooks of the upper shearing-rod being arranged between those of the compression-rod and the lower shearing-rod, substantially as set forth.

Witness my hand this 31st day of January, 1906.
